United States Patent Office

Des. 193,316
Patented July 31, 1962

193,316

PHOTOGRAPHIC PROJECTOR

William R. King, Denver, Colo., assignor to Minneapolis-Honeywell Regulator Company, Minneapolis, Minn., a corporation of Delaware

Filed Sept. 22, 1961, Ser. No. 66,857

Term of patent 14 years

(Cl. D61—1)

Fig 1

Fig 2

Fig 3

Fig 4

FIGURE 1 is a front perspective view of a photographic projector, showing my new design,

FIGURE 2 is a right side elevational view thereof,

FIGURE 3 is a rear elevational view thereof, and

FIGURE 4 is a bottom view thereof.

I claim:

The ornamental design for a photographic projector, substantially as shown.
